UNITED STATES PATENT OFFICE.

EDWIN J. PRINDLE, OF WASHINGTON, DISTRICT OF COLUMBIA.

LAST-BLOCK.

No. 898,989.

Specification of Letters Patent.

Patented Sept. 15, 1908.

Original application filed August 14, 1901, Serial No. 72,081. Divided and this application filed March 6, 1905.
Serial No. 248,568.

To all whom it may concern:

Be it known that I, EDWIN J. PRINDLE, of Washington, in the District of Columbia, have invented a certain new and useful Improvement in Last - Blocks, and do hereby declare that the following is a full, clear, and exact description thereof, reference being had to the accompanying drawings, in which:

Figure 1 is a perspective view of a last-block embodying my invention: Figs. 2 and 3 are, respectively, side and end elevations of the block illustrated in Fig. 1.

The object of my invention has been to provide a last-block from which last parts 15 can be turned, which blocks shall have geometrical hinge-attaching or other geometrical surfaces formed thereon before and preparatory to the turning operation; and, to such ends my invention:—consists in the 20 last block hereinafter specified.

I have chosen to illustrate my invention by means of a block which is prepared for the turning operation to form the fore-part of the last illustrated in Patent No. 648,525, granted 25 to me May 1st, 1900, but the invention is applicable to a block for forming any other last-part.

The block A is provided with a surface B that is to form one of the geometrical abutting or attaching, or other geometrical surfaces in the last, or that bears a definite relation to such a surface, which relation may be that of identity or any other geometric relation, such as parallelism to such surface at a 30 definite distance therefrom. A slot C, or other means of attachment, is provided, whereby the block may be secured to a chuck. In the instance chosen for illustration, the slot c is of proper form to receive the fore- 35 part hinge-plate and wedge of the last illustrated in my said patent. Any means of attachment, however, may be used by which the block may be conveniently secured to a chuck or to a last hinge. The side surfaces 40 of the block may be of any desired shape. The end surface D may be a plane or other geometrical surface if desired.

While I have chosen the above form of block to illustrate my invention, I desire it to be understood that there are many other forms under which the invention could be practiced, and I do not desire to be limited beyond the scope of my claims and the requirements of the prior art.

This application is a division of my application No. 72,081, filed August 14th, 1901 for improvements in and relating to lasts.

Having thus described my invention, what I claim is:

1. A block for forming last parts, such 60 block having two or more geometrical surfaces formed thereon in the same relation they are to bear in the finished last part.

2. A block for forming last parts, such block having an abutting surface and a geometrical hinge - attaching surface formed 65 thereon in the relation which such surfaces are to have in the finished last part.

3. A block for forming last parts, such block having a finished surface, and having a 70 slot or opening in which the hinge of the last is adapted to be received.

4. A block for forming last parts, such block having a finished surface and having hinge-attaching means on the end thereof on 75 which such surface is formed.

5. A block for forming last parts, such block having a finished surface, and having dog attaching means on the end thereof, on 80 which such surface is formed.

6. As a new article of manufacture, a last-block formed with a squared end to serve as an abutting face in a finished last.

7. As a new article of manufacture, a last-block formed with a squared end which is to 85 serve as an abutting face in the finished last, said block having a squared toe portion.

In testimony that I claim the foregoing I have hereunto set my hand.

EDWIN J. PRINDLE
